UNITED STATES PATENT OFFICE

155,321

DESIGN FOR A GRILLE GUARD FOR AUTOMOBILE RADIATORS

Harry Phillips, New York, N. Y., assignor to State
Welding Works, Inc., New York, N. Y.

Application September 15, 1947, Serial No. 141,400

Term of patent 3½ years

(Cl. D14—6)

To all whom it may concern:

Be it known that I, Harry Phillips, a citizen of the United States, residing at New York city, in the county of the Bronx and State of New York, have invented a new, original, and ornamental Design for a Grille Guard for Automobile Radiators, of which the following is a specification; reference being had to the accompanying drawing, forming a part thereof.

Fig. 1 is a perspective view of a grille guard for automobile radiators, showing my new design.

Fig. 2 is a front elevation thereof.

Fig. 3 is a top plan view thereof.

The characteristic features of my design reside in the portions shown by means of full lines in the drawing.

I claim:

The ornamental design for a grille guard for automobile radiators, substantially as shown and described.

HARRY PHILLIPS.
